UNITED STATES PATENT OFFICE.

CHARLES A. MAY, OF TRENTON, NEW JERSEY, ASSIGNOR TO MADDOCK POTTERY COMPANY, INCORPORATED, OF TRENTON, NEW JERSEY, A CORPORATION OF NEW JERSEY.

DESIGN FOR A PLATE OR SIMILAR ARTICLE.

40,290.

Specification for Design.

Patented Oct. 12, 1909.

Application filed July 23, 1909. Serial No. 509,235. Term of patent 7 years.

To all whom it may concern:

Be it known that I, CHARLES A. MAY, a citizen of the United States, residing at Trenton, in the county of Mercer and State of New Jersey, have invented a new, original, and ornamental Design for Plates or Similar Articles, of which the following is a specification, reference being had to the accompanying drawing, forming part thereof.

The figure is a plan view of a plate

broken away in part, showing my new design.

I claim:

The ornamental design for a plate or similar article, as shown.

CHARLES A. MAY.

Witnesses:

C. E. SCUDDER,
THOS. F. TUNSTALL.
